UNITED STATES PATENT OFFICE.

PAUL KAMINSKI, OF NONNENDAMM, NEAR BERLIN, GERMANY, ASSIGNOR TO SIEMENS & HALSKE A. G., OF BERLIN, GERMANY, A CORPORATION OF GERMANY.

ELECTRIC SYSTEM FOR TRANSMITTING ANGULAR POSITIONS.

1,122,942.

Specification of Letters Patent. Patented Dec. 29, 1914.

Application filed August 15, 1913. Serial No. 784,983.

To all whom it may concern:

Be it known that I, PAUL KAMINSKI, a German citizen, and resident of Nonnendamm, near Berlin, Germany, have invented certain new and useful Improvements in Electric Systems for Transmitting Angular Positions, of which the following is a specification.

My invention relates to a system of the kind in which the adjustment is obtained by means of rotors which are commonly influencing the position of the object upon which the position is to be produced, and especially to a novel system of this character for producing different positions of instruments such as telescopes, dipters or contrivances for taking aim upon any desired object such as search lights and the like by means of a plurality of motors, one of said motors effecting the coarse, the other the fine adjustment in any desired plurality of steps.

My present invention more particularly consists of an improvement of the system forming part of an application for patent Ser. No. 599,173, filed by H. Barkhausen and myself under date of Dec. 24, 1910. In the system described in the aforesaid application the adjustment of the several steps can be accomplished either in succession to each other or so that the several adjustments are dependent on each other in a certain manner. My present invention, now, comprises a modification of this system in that the adjusting devices are electrically independent of each other so that the adjustment of the coarse and the fine steps may be accomplished simultaneously. In brief my present invention consists in interposing a differential gear between the motors commonly effecting the displacement of the object on the one hand and the object upon which the motion shall be transmitted on the other hand. Also the motors by providing proper ratios of gearing may be so chosen that their sizes will be proportioned to the range of adjustment.

My invention will be more fully understood by reference to the accompanying drawing which shows in a diagrammatic view one form for carrying my invention into effect.

The sending apparatus G consists of two sending elements e_1 , e_2 which may be coupled to each other by gears or the like in

such a way that one system, for instance e_2 makes several revolutions, while the other system e_1 is making at most one revolution for traversing its entire measuring range. The two sending elements e_1 , e_2 , now, act in 60 a well known manner upon the receiving element v_1 , v_2 which are located at the receiving station E. The rotors of these systems are so constructed that upon being angularly displaced they will act upon the 65 circuits for the driving motors M_1 , M_2 , the former, for instance, being destined for the coarse and the latter for the fine adjustment. Both motors work upon a differential gear P whose intermediate 70 wheel p is rotatably mounted upon an arm serving for the rotation of the axle w for displacing the object which shall follow the motion of the sending apparatus. From this axle w furthermore, a device is operated for again interrupting the contacts provided on the receiving elements after 75 said object is in its proper position, and therewith cause the standstill of the motors M_1 and M_2 . If, for instance, an adjustment 80 is made at the sending station G, then at the receiving station E the rotors of the two receiving elements v_1 and v_2 in the arrangement shown will establish a contact at i and k respectively and therewith close the 85 circuits for the motors M_1 and M_2 . Both motors accordingly will start. If the motor M_1 , for the coarse adjustment has effected a corresponding angular motion of the object by the rotation of the planetary gear p_1 , then 90 by the axle w , the interposed gear z and the worm gear s , the contact at i will again be interrupted, at the same time interrupting the operating current for the motor M_1 . The motor M_2 will continue to operate until 95 the fine adjustment has been accomplished to the desired degree, and by a corresponding motion of the planetary gear p_2 , this motor will still further turn the object to be adjusted. The displacement of the object, on the other hand, will simultaneously 100 act by means of the gear z and further transmission members u upon the contacts k , which remain closed until the fine adjustment also has reached its proper value. As 105 either motor traverses the entire scale of the system to be adjusted and the motor for the fine adjustment consequently will have to pass only through a small range, this latter motor may act upon the adjusting de- 110

vice with a greater ratio of gearing and may, therefore, be made of smaller size than the motor for the coarse adjustment.

The mechanism of the transmitting apparatus G and the receiving apparatus E each consists of a single phase alternating current field, which is excited from a source of current common to the transmitting and receiving device. The wiring is not shown here as it does not concern the present invention. Within the field of each of these devices a three-phase alternating current rotor is located, the rotors of the corresponding transmitting and receiving instruments being connected by the three phase wires. In the drawings these three wires are merely shown as emanating from the instruments. Moreover, the rotor of the transmitter G is connected with the handle for setting the desired angular position, whereas the rotor of the receiver v_1 — v_2 are each connected with a contact spring i — k respectively. The result is that when the transmitter rotor is moved angularly, the receiver armature according to well known laws will follow into the same angular position. Transmitting devices of this character are now well known in the art, so that their detail description and illustration has been omitted in the present application.

Instead of the movable contacts i and k for the operation of the motors, as shown in the drawing, also fixed contacts may be employed; in this case for adjustment the stators of v_1 and v_2 are turned back to the same extent as the rotors have been adjusted before from the sending station. It is of course understood that the switching for the circuits for driving the motors may be done by relays which are properly interposed. It is also possible, as well understood by the art, to omit the gear between the rotors of the sending elements. In this case preferably either rotor should be provided with means for retaining the rotor in a plurality of

proper angular positions and then the adjusting of either rotor made by a separate handle. Also the senders may be immediately connected with a diopter or any contrivance for taking aim as well known to the art.

Having thus described my invention I claim as new and desire to secure by Letters Patent of the United States:—

1. An electric system for producing angular positions consisting of a sending element for fine adjustment, a sending element for coarse adjustment, corresponding receiving elements which are respectively connected with said sending elements, a motor electrically controlled from said receiving element for coarse adjustment, a second electric motor controlled from said receiving element for fine adjustment and a differential gear interposed between each of said motors and the object upon which the angular position shall be produced.

2. An electric system for producing angular positions consisting of a sending element for fine adjustment, a sending element for coarse adjustment, corresponding receiving elements which are respectively connected with said sending elements, a motor electrically controlled from said receiving element for coarse adjustment, a second motor electrically controlled from said receiving element for fine adjustment, a differential gear interposed between each of said motors and the object upon which the angular position shall be produced, said motor for fine adjustment being connected with a higher ratio of gearing to said object than said motor for coarse adjustment.

In witness whereof I have hereunto set my signature in the presence of two subscribing witnesses.

PAUL KAMINSKI.
